UNITED STATES PATENT OFFICE

2,200,297

COMBINED PHONOGRAPH AND RADIO

Henry T. Roberts, Chicago, Ill., assignor to
Seeburg Radio Corporation, Chicago, Ill., a corporation of Illinois

Application March 21, 1938, Serial No. 197,074

3 Claims. (Cl. 312—189)

As one object of my present invention, I propose to provide a unitary musical instrument having embodied therein both a radio and a phonograph, the apparatus and arrangement of the various parts thereof being substantially simple and inexpensive from a manufacturing standpoint.

Another object is to provide a phonograph mechanism and radio apparatus so arranged and mounted in a single casing that the radio side 10 and the phonograph side thereof can be designed substantially symmetrically with covers provided for both the radio compartment and the phonograph compartment, the covers being similar in external appearance when closed but different 15 in construction and operation.

A further object is to provide a cabinet in which phonographic apparatus is mounted on one side adjacent the top thereof and control mechanism for radio apparatus is mounted on the other side 20 adjacent the top, there being space below the phonograph apparatus for storing a considerable number of records, as, for instance, in record albums, and there being space below the radio apparatus for a loud speaker and its sound chamber, the loud speaker being operable from either 25 the phonograph apparatus or the radio apparatus whereby a single sound emitting member functions for both.

Still a further object is to provide a lid for the 30 phonograph compartment which is hinged so that it can be swung open and a cover member that can be slid back relative to the phonograph compartment lid to open the phonograph compartment and which is carried by the lid and to provide for the radio compartment a similar cover 35 which can be slid back relative to a stationary lid for the radio compartment.

With the foregoing and other objects in view, my invention consists in the construction, arrangement and combination of the various parts 40 of my device, whereby the objects contemplated are attained, as hereinafter more fully set forth, pointed out in my claims, and illustrated in the accompanying drawings, in which:

45 Figure 1 is a perspective view of a combined radio and phonograph embodying my invention.

Figure 2 is an enlarged sectional view on the line 2—2 of Figure 1 showing a radio apparatus and loud speaker.

50 Figure 3 is a similar sectional view showing a portion of the top of Figure 2 with the parts in a different position.

55 Figure 4 is a sectional view on the line 4—4 of Figure 1 taken through the phonograph and record compartments of my device.

Figure 5 is a similar sectional view of the top portion of Figure 4 showing the parts in a different position.

Figure 6 is a sectional view on the line 6—6 of Figure 1 showing a record storage compartment 5 and a loud speaker compartment; and

Figure 7 is an enlarged sectional view on the line 7—7 of Figure 1 showing a removable cover board for wave channel adjusting means of the radio apparatus.

10 On the accompanying drawings I have used the reference character B to indicate a pair of base supporting members for my cabinet. Extending upwardly from the base members B are side members 10 at the front of which I arrange ornamental pilasters 12. The cabinet proper has a plurality of members forming its front wall and likewise a plurality of members forming its back wall between which and the side walls 10 there are four compartments. These compartments are 20 a radio apparatus compartment R, a loud speaker compartment S, a phonograph apparatus compartment P and a phonograph record compartment PR.

25 The compartment R (see Fig. 2) has a partition member 14 on which is supported a radio chassis 15. A top member or lid 16 is provided for the compartment R which extends from the back of the cabinet and part way toward the front thereof as shown. The distance between the front edge 30 of the top member 16 and a front panel 17 of the radio compartment R is spanned by a control panel 18. Various control knobs, which are shown by way of illustration at 19 and 20 for the radio apparatus 15, are mounted on the panel 18. The 35 panel 18 is preferably arranged at an acute angle to the horizontal so that the knobs 19 and 20 can be readily manipulated by an operator standing in front of the cabinet.

The knobs 19 and 20 are normally covered by 40 a cover member 21. The member 21 in its covering position has its forward edge, which is provided with a strip of felt 22, resting on the panel 18 and its rear edge supported by limiting pins 23. The side edges of the cover member 21 are 45 adapted to slide on supporting strips or cleats 24 secured to the sides of the radio compartment R. When it is desirable to expose the knobs 19 and 20 for manipulation, the cover member 21 is slid rearwardly on the cleats 24 to the position shown 50 by dotted lines in Figure 2 and by full lines in Figure 3.

The radio apparatus 15 includes wave channel condensers 25 having adjusting screws 26. To facilitate access to the screws 26 when it is neces- 55

sary to adjust them, a cover board 27 is provided which can be readily removed. As shown in Figure 7, the cover board 27 has depressions 28 coacting with spring pressed retainer pins 29 so that 5 the board can be merely slipped into and out of position as desired. When in position as illustrated, the pins retain the board against accidental dislodgement.

Below the partition 14 I mount a loud speaker 10 30 on a front baffle board 32 of the cabinet. This speaker is mounted in the speaker compartment S and is adapted to be actuated by either the radio apparatus 15 or an electric pick-up device of the phonographic apparatus P as will be hereinafter 15 described.

The phonographic apparatus compartment P has therein a supporting board 31. A phonograph motor 32a is mounted thereon and operates a turntable 33. An electric pick-up 34 is adapted 20 to coact with a record on the turntable 33 and is suitably wired in a well-known manner with the loud speaker 30 and with a switch 35 adapted to effect electrical connection of a power source with the motor 32a and electric connections between 25 the pick-up 34 and the loud speaker 30. The switch 35 is conveniently mounted on the board 31 so that it is in position to be manipulated by the operator when a cover member 21a is slid back to the dotted position of Figure 4 or to the 30 full line position of Figure 5.

The cover member 21a is supported by arms 26a which in turn are supported at their rear ends on a hinged cover or lid 16a. Thus the phonograph compartment P can be opened as shown 35 in Figure 5 or further opened if desired as shown by dot and dash lines in Figure 4, with the cover member 21a being carried by and opening with the lid 16a. A partition 36 is provided below the motor 32a. Below this partition there is a shelf 40 38 and a bottom member 39. The shelf 38 and the bottom member 39 are adapted to support record albums 40 which contain various records 41 to be used on the turntable 33. Access may be had to the phonograph record compartment PR 45 through a door 42 hinged as at 43. The door is shown in open position by dot and dash lines in Figure 6.

By the arrangement of the parts of the cabinet and the apparatus therein as disclosed, I am able 50 to provide considerable room for storing records and yet make a compact cabinet in which the phonograph mechanism, the radio apparatus and the loud speaker can be mounted without interference with each other. Either the phonograph 55 or the radio can be operated and while the one is being operated, the other can be neatly covered by the covers 21 or 21a. When the apparatus is

not in use, both cover members can be closed, thus giving to the device a neat appearance somewhat similar to a piano when in closed position. Since the loud speaker is operated by either the phonograph mechanism or the radio apparatus, it is 5 unnecessary to make the cabinet large enough to contain both a phonograph horn and a radio speaker.

Some changes may be made in the construction and arrangement of the parts of my device without departing from the real spirit and purpose of my invention. I therefore intend for my claims to cover any modified forms of structure or use of mechanical equivalents which may be reasonably included within their scope. 15

I claim as my invention:

1. In a structure as disclosed, a cabinet, a mechanism compartment therein, a lid for partially closing said compartment, said lid being hinged to said cabinet, guide means on said lid, 20 a cover for completing the closure of said compartment supported on said guides and slidably thereon for partially opening said compartment, said cover being raised thereby with said lid when said lid is raised for fully opening said compartment. 25

2. In a structure of the class described, a cabinet, mechanism and apparatus compartments therein adjacent the top thereof, a pair of compartments below said mechanism and apparatus 30 compartments respectively, and slidably mounted covers for said mechanism and apparatus compartments, said covers being similar in appearance and aligned with each other to give a symmetrical appearance to said compartments when 35 said cover members are closed, and a hinged lid for said mechanism compartment, said lid constituting a part of the top wall of said cabinet and being similar in appearance to the fixed section of the top wall of said cabinet, the cover member 40 for said mechanism compartment being carried by said lid and thereby raised to a position above said mechanism compartment when said lid is swung to open position.

3. In a cabinet construction, a cabinet having 45 compartments, a top wall covering said compartments, slidably mounted covers for said compartments, said covers being similar in appearance and aligned with each other to give a symmetrical appearance to said compartments when said cover 50 members are closed, and a hinged lid constituting a part of the top wall of said cabinet and being similar in appearance to the fixed part of said top wall, one of said cover members being carried by said lid. 55

HENRY T. ROBERTS.
